UNITED STATES PATENT OFFICE.

JACOB MYTKO, OF DEPEW, NEW YORK.

LIGHTED PLATE.

Application filed July 17, 1925. Serial No. 44,274.

To all whom it may concern:

Be it known that I, JACOB MYTKO, a citizen of the United States, residing at Depew, in the county of Erie and State of New York, have invented new and useful Improvements in Lighted Plates, of which the following is a specification.

This invention relates to improvements in lighting devices for application upon the front and rear portions of motor vehicles for illuminating the respective license plates therefore, in order that the said license plates may be displayed to great advantage and the correct reading thereof be easily ascertained from a remote point both in the front and rear of the respective vehicle to which the present invention is applied.

A further object of my invention resides in the provision of a tail lamp constructed in the rear casing in order that a combined illuminated tail lamp and license plate is combined in one casing and illuminated by a single lamp bulb whereby there is a material saving of the electrical charge from the vehicle storage battery.

With the above and other objects in view, the invention further includes the following novel features and details of construction, to be hereinafter more fully described, illustrated in the accompanying drawing and pointed out in the appended claims.

In the drawing:

Figure 1 is a front elevation of my invention.

Figure 2 is a transverse section taken on line 2-2 of Figure 1.

Figure 3 is a vertical sectional view taken on line 3-3 of Figure 1.

Figure 4 is a front elevation of the rear plate within the compartment defined for the license plate.

Figure 5 is a fragmentary end view of the compartment showing a locking means therefore.

Referring to the drawing in detail, wherein like characters of reference denote corresponding parts, the reference character 10 indicates a lamp box having a lamp socket 11 extending through the rear end thereof and mounting an incandescent lamp bulb 12 upon its inner end and within the lamp casing 10 and directly behind the lens 13 which is preferably red and mounted in a similar manner to the usual and conventional form of tail lamp.

Arranged upon the bottom or under side of the said lamp casing 10 and being illuminated by the bulb 12 through an opening or slot 14 provided in the lower side 60 of the lamp casing 10 is license plate compartment 15 having its forward end open and providing a rear wall 16 within which spring fingers 17 are secured to the inner sides thereof and having their respective ends tensioned against the rear side of the license plate 18 which in turn has a lens or plate of clear glass, as indicated at 19, arranged upon its face and which in turn has its marginal edges bearing against a gasket or packing 20 directly behind and lying flush with an annular flange 21 arranged within the said license plate compartment 15 in order that no abrasion will thus occur upon the said lens or glass plate 75 19 and hence eliminate the cracking or breaking thereof and in rendering clearly discernible the correct reading of the respective license plate positioned directly behind the said lens 19. It will thus be noted that the light thrown from the incandescent lamp bulb 12 will pass through the opening 14 within the bottom of the said lamp casing 10 and into the license plate compartment 15 and upon the said lens 19 whereby the license plate 18 positioned directly therebehind, will be clearly illuminated.

In order to provide means for preventing theft of the said license plate 19 within the said compartment 15, I provide a lock 21' 90 upon the rear wall 16 having its shank 22 extending within an opening, not shown, within an offset bracket 23 arranged upon one side of the license plate compartment 15. The rear wall 16 is hingedly secured as at 95 24 to the rear edge of the opposite side wall composing the license plate compartment 15 in order that the lock when so opened and the rear wall 16 swung upon its pivotal point or hinges 24 will allow the user to readily and easily remove a license plate in the replacement of a new one for the ensuing year.

It is quite obvious that from the foregoing description and accompanying drawing that although I have shown the preferred embodiment of my invention as composing a combined tail lamp and means for illuminating the vehicle license plate, that I do not intend to limit myself to this one form of invention but that the tail lamp or lens as indicated at 13 may be eliminated

and the flat surface compose the forward portion of the said lamp casing 10 when using the said device upon the front of a vehicle where a tail lamp is not used and 5 unnecessary.

The invention is susceptible of various changes in its form, proportions and minor details of construction, and the right is herein reserved to make such changes as 10 properly fall within the scope of the appended claims.

Having described my invention what is claimed is:—

1. An illuminated license plate of the 15 character described comprising a lamp casing having a tail lamp positioned upon its forward end, a transversely disposed elongated compartment arranged upon the under side of and having communication 20 with the said lamp casing, a license plate positioned within the said compartment, a lens for the license plate, spring fingers positioned upon the forward side of the compartment rear wall for holding the license 25 plate and lens therefore in a desired position, and means included upon the said rear

wall for opening and locking the same in removing and replacing the license plate for the ensuing year.

2. An illuminated license plate of the 30 character described comprising a lamp casing having a tail lamp lens mounted upon its forward end, a transversely disposed elongated compartment arranged upon the under side and having communication with 35 the said lamp casing, the said compartment having a centrally mounted annular flange and rear wall therefore, a license plate and lens therefore positioned directly behind the flange, spring fingers arranged upon the 40 forward sides of the rear wall and tensioned against the license plate for positioning the same and the lens therefore against the flange, and locking and swinging means included upon the rear wall 45 whereby the user may readily remove and replace the license plate for the ensuing year.

In testimony whereof I affix my signature.

JACOB MYTKO.
